PRODUCTION OF TETRAALKYLSTILBENE
QUINONES AND TETRAALKOXYSTIL-
BENE QUINONES

William K. T. Gleim, Orland Park, Alexander Gaydasch, Brookfield, and Robert H. Rosenwald, Western Springs, Ill., assignors to Universal Oil Products Company, Chicago, Ill., a corporation of Delaware

No Drawing. Application June 17, 1950,
Serial No. 168,846

12 Claims. (Cl. 260—396)

1

This invention relates to a process for preparing tetraalkylstilbene quinones and tetraalkoxy-stilbene quinones. More particularly, this invention relates to a process for preparing tetraalkyl-stilbene quinones and tetraalkoxystilbene quinones in which each alkyl and alkoxy group contains from one to six carbon atoms.

An object of this invention is to produce an organic compound selected from the members of the group consisting of a tetraalkylstilbene quinone and a tetraalkoxystilbene quinone.

Another object of this invention is to produce a 3,5,3',5'-tetraalkylstilbene quinone.

Still another object of this invention is to produce a 3,5,3',5'-tetraalkoxystilbene quinone.

An additional object of this invention is to produce 3,5,3',5'-tetra-tert-butyl-stilbene quinone.

Still another object of this invention is to produce 3,5,3',5'-tetra-methyl-stilbene quinone.

One embodiment of this invention relates to a process for producing a tetra-substituted stilbene quinone in which the substituents are selected from the members of the group consisting of an alkyl group and an alkoxy group each containing from one to six carbon atoms which comprises oxidizing a member of the group consisting of a dialkyl-p-cresol and a dialkoxy-p-cresol having alkyl and alkoxy groups containing from one to six carbon atoms.

Another embodiment of this invention relates to a process for producing a polyalkylstilbene quinone which comprises oxidizing a polyalkylphenol in which the alkyl groups contain from one to six carbon atoms.

Still another embodiment of this invention relates to a process for producing a tetra-alkylstilbene quinone which comprises oxidizing a 2,6-di-alkyl-p-cresol having alkyl groups containing from one to six carbon atoms.

A further embodiment of this invention relates to a process for producing tetramethylstilbene quinone which comprises oxidizing 2,6-dimethyl-p-cresol.

A still further embodiment of this invention relates to a process for producing tetra-tert-butyl-stilbene quinone which comprises oxidizing 2,6-di-tert-butyl-p-cresol.

We have found that 2,6-dialkyl-p-cresol and 2,6-dialkoxy-p-cresol which have from one to six carbon atoms in said alkyl and alkoxy groups can be oxidized readily to form certain tetra-alkyl-stilbene quinones and tetra-alkoxy-stilbene

quinones which may be represented by the equation:

in which R represents a member of the group consisting of an alkyl group and an alkoxy group having from one to six carbon atoms.

We have oxidized 2,6-dialkyl-p-cresol by different means including use of alkali metal chlorates, ferricyanides, lead dioxide, silver oxide, and the like, to produce tetraalkylstilbene quinones. Such an oxidation is carried out, for example, by heating a 2,6-dialkyl-p-cresol at a temperature of from about 20° to about 100° C. with sodium chlorate and an aqueous solution containing sulfuric acid or another mineral acid.

In another method of effecting such an oxidation, a pentane solution of a 2,6-dialkyl-p-cresol is contacted with an aqueous solution containing 10% by weight of sodium hydroxide and then this mixture is stirred while an aqueous solution of potassium ferricyanide is added thereto to form a tetraalkylstilbene quinone.

Similar oxidation treatment of a 2,6-dialkoxy-p-cresol produces a tetraalkoxystilbene quinone.

These 2,6-dialkyl-p-cresol and 2,6-dialkoxy-p-cresols are also referred to as 2,6-dialkyl-4-methyl phenols and 2,6-di-alkoxy-4-methylphenols.

Tetra-alkylstilbene quinones and tetra-alkoxy-stilbene quinones which are formed by this process are useful as dyes, germicides, and also as intermediates in the synthesis of other organic compounds and particularly in the synthesis of synthetic sex hormones, plant hormones, and plant growth regulators. These compounds are represented by the following structural formulae:

wherein each of R₁ to R₆ separately represents a member of the group consisting of hydrogen, alkyl, alkoxy, —NR₂, —CH₂NR₂, and —CH₂OR. These compounds are useful as bactericides, fungicides, insecticides, arachnidicides, rodenticides, also as antibacteriological agents, chemotherapeutic agents, antiprotozoa agents and trypanocidal agents. Some of these compounds are also useful in the control of yeasts, viruses, malaria and other parasites.

Certain examples of the aforementioned tetra-substituted stilbene quinones and their reduction products are represented by the following formulae:

Tetra-alkylstilbene quinones can be reduced to form the corresponding 4,4'-stilbene diols and α, α' -dihydrostilbene diols which are useful as synthetic sex hormones and synthetic plant hormones. The tetra-alkylstilbene quinones and tetra-alkoxystilbene quinones are also reduced by catalytic hydrogenation at mild conditions to form dihydroxy tetra-alkyl(or tetra-alkoxy)stilbene and dihydrostilbenes which are useful in the syntheses of other organic compounds. Thus 3,5,3',5' - tetra - alkyl - stilbene quinone and 3,5,3',5'-tetra-alkoxy-stilbene quinone are hydrogenated to form 4,4'-dihydroxy-3,5,3',5'-tetraalkylstilbene, 4,4'-dihydroxy-3,5,3',5'-tetraalkoxystilbene, α, α' -dihydro-3,5,3',5'-tetra-alkylstilbene and α, α' -dihydro-3,5,3',5'-tetra-alkoxy-stilbene.

The nature of the present invention is illustrated further by the following examples which should not be misconstrued to limit unduly the generally broad scope of the invention.

Example I

22 grams of 2,6-di-*tert*-butyl-p-cresol was treated with 4 grams of sodium chlorate in 150 ml. of an aqueous solution containing 2% by weight of sulfuric acid with 0.25 gram vanadium pentoxide as a catalyst at a temperature of 70-80° C. for a time of 5 hours, during which time the reaction mixture was stirred continuously. This treatment yielded a brick red compound which melted at a temperature of from between 286° and 296° C. This compound was found to be 3,5,3',5'-tetra-*tert*-butylstilbene quinone.

Example II.

In another run, a solution consisting of 200 ml. of pentane and 25 grams of 2,6-di-*tert*-butyl-4-methylphenol was contacted with 100 ml. of an aqueous solution containing 10% by weight of sodium hydroxide. This mixture was stirred

continuously at a temperature of 28 to 32° C. while an aqueous solution consisting of 400 ml. of water and 104 grams of potassium ferricyanide was added thereto during a time of 20 minutes. This oxidation treatment also yielded a brick red material having about the same melting point as that referred to in Example I. The brick red compound had a relatively low solubility in cyclohexane and accordingly made it difficult to obtain an accurate molecular weight determination in this solvent. Nevertheless, the two values obtained, namely 437 and 566 each plus or minus 10% gave evidence that the main reaction occurring was a dimerization of the charged cresol to form tetra-tert-butyl-stilbene quinone.

The 3,5,3',5'-tetra-tert-butyl-stilbene quinone so formed was soluble in concentrated sulfuric acid but had a relatively low solubility in benzene, carbon tetrachloride, acetone, acetic anhydride, and ethyl acetate. It was practically insoluble in concentrated hydrochloric acid and in Claisen's solution.

When some of the 3,5,3',5'-tetra-tert-butyl-stilbene quinone was reduced with sodium in isooctyl alcohol the color changed from yellowish-red through green to a blue-green. Also the 3,5,3',5'-tetra-tert-butyl-stilbene quinone was reduced by stannous chloride to form the corresponding 4,4'-stilbene diol. The 3,5,3',5'-tetra-tert-butyl-stilbene quinone also added hydrogen chloride in glacial acetic acid to form 4,4'-di-hydroxy-*a,a'*-dichloro-3,5,3',5'-tetra-tert-butyl-stilbene having the following structural formula:

The catalytic reduction of 3,5,3',5'-tetra-tert-butyl-stilbene quinone by hydrogen in ethyl acetate solution in the presence of palladium on barium sulfate at a temperature of 100° C. and at a pressure of 100 atmospheres produced a substantial amount of 4,4'-dihydroxy-3,5,3',5'-tetra-tert-butyl- α,α' -dihydrostilbene having the structural formula:

Example III

Five grams of mesitol (2,4,6-trimethylphenol) was oxidized with 25 grams of silver oxide suspended in 350 ml. chloroform. This oxidation yielded a deep red colored compound with a melting point of 222° to 224° C. corresponding to that of synthetically prepared 3,5,3',5'-tetra-methyl-stilbene quinone and giving no melting point depression on a mixture of the red oxidation product and the synthetically prepared quinone.

The synthesis used for preparing 3,5,3',5'-tetra-methylstilbene quinone consisted in treating 2,6-dimethylphenol with formaldehyde in 5% sodium hydroxide solution to yield 3,5-di-methyl-4-hydroxy-benzyl alcohol which was then treated with hydrogen bromide gas in chloroform to produce 3,5-di-methyl-4-hydroxy-benzyl bromide, the latter then being shaken in ether solution with a concentrated solution of sodium bicarbonate to form 3,5,3',5' - tetramethylstilbene quinone.

Example IV

20 grams of 2,4-di-methyl-6-tert-butyl-phenol were dissolved in 100 ml. of pentane and this solution was then contacted with 100 ml. of an aqueous solution containing 10% by weight of sodium hydroxide. This mixture was then stirred continuously at a temperature of 25-30° C. while an aqueous solution consisting of 200 ml. of water and 52 grams of potassium ferricyanide was added thereto during a time of 30 minutes. This oxidation treatment yielded a red solid material which was found to be 3,3'-di-tert-butyl-5,5'-dimethylstilbene quinone.

Example V

In a run similar to that described in Example IV, 2,6-di-tert-butyl-4-methyl-phenol was oxidized by potassium ferricyanide to produce an orange-red, colored dye which was useful for dyeing cloth and also for dyeing gasoline.

We claim as our invention:

1. A process for producing a tetra-substituted stilbene quinone in which the substituents are selected from the members of the group consisting of an alkyl group and an alkoxy group each containing from one to six carbon atoms which comprises oxidizing a member of the group consisting of a dialkyl-p-cresol and a di-alkoxy-p-cresol having alkyl and alkoxy groups containing from one to six carbon atoms by heating the same at a temperature of from about 20° to about 100° C. with an oxidizing agent selected from the group consisting of alkali metal chlorates and ferricyanides, lead dioxide and silver oxide.

2. A process for producing a polyalkylstilbene quinone which comprises oxidizing a polyalkyl-phenol in which the alkyl groups contain from one to six carbon atoms by heating the same at a temperature of from about 20° to about 100° C. with an oxidizing agent selected from the group consisting of alkali metal chlorates and ferricyanides, lead dioxide and silver oxide.

3. A process for producing a tetra-alkylstilbene quinone which comprises oxidizing a 2,6-dialkyl-p-cresol having alkyl groups containing from one to six carbon atoms by heating the same at a temperature of from about 20° to about 100° C. with an oxidizing agent selected from the group consisting of alkali metal chlorates and ferricyanides, lead dioxide and silver oxide.

4. A process for producing tetramethylstilbene quinone which comprises oxidizing 2,6-dimethyl-p-cresol by heating the same at a temperature of from about 20° to about 100° C. with an oxidizing agent selected from the group consisting of alkali metal chlorates and ferricyanides, lead dioxide and silver oxide.

5. A process for producing tetra-tert-butylstilbene quinone which comprises oxidizing 2,6-di-tert-butyl-p-cresol by heating the same at a temperature of from about 20° to about 100° C. with an oxidizing agent selected from the group consisting of alkali metal chlorates and ferricyanides, lead dioxide and silver oxide.

6. A process for producing a tetraalkylstilbene quinone which comprises oxidizing a 2,6-dialkyl-p-cresol having alkyl groups containing from one to six carbon atoms by heating said cresol

with a mixture of an alkali metal chlorate and an aqueous solution of a mineral acid at a temperature of from about 20° to about 100° C.

5 7. A process for producing a tetraalkylstilbene quinone which comprises oxidizing a 2,6-dialkyl-p-cresol having alkyl groups containing from one to six carbon atoms by heating said cresol with a mixture of sodium chlorate and an aqueous solution of sulfuric acid at a temperature of from about 70° to about 80° C.

10 8. A process for producing tetramethylstilbene quinone which comprises oxidizing 2,6-dimethyl-p-cresol by heating said cresol with a mixture of sodium chlorate and an aqueous solution of sulfuric acid at a temperature of from about 70° to about 80° C.

15 9. A process for producing tetra-tert-butylstilbene quinone which comprises oxidizing 2,6-di-tert-butyl-p-cresol by heating said cresol with a mixture of sodium chlorate and an aqueous solution of sulfuric acid at a temperature of from about 70° to about 80° C.

20 10. A process for producing a tetra-substituted stilbene quinone in which the substituents are selected from the members of the group consisting of an alkyl group and an alkoxy group each containing from one to six carbon atoms which comprises treating a member of the group consisting of a di-alkyl-p-cresol and a di-alkoxy-p-cresol in which the alkyl and alkoxy groups contain from one to six carbon atoms with potassium ferricyanide and recovering from the resultant oxidation product a tetra-substituted stilbene quinone.

25 11. A process for producing a tetra-substituted stilbene quinone in which the substituents are selected from the members of the group consisting of an alkyl group and an alkoxy group each containing from one to six carbon atoms which comprises treating a member of the group consisting of a di-alkyl-p-cresol and a di-alkoxy-p-cresol in which the alkyl and alkoxy groups contain from one to six carbon atoms with potassium ferricyanide and recovering from the resultant oxidation product a tetra-substituted stilbene quinone.

30 12. A process for producing a tetra-substituted stilbene quinone in which the substituents are selected from the members of the group consisting of an alkyl group and an alkoxy group each containing from one to six carbon atoms which comprises treating a member of the group consisting of a di-alkyl-p-cresol and a di-alkoxy-p-cresol in which the alkyl and alkoxy groups contain from one to six carbon atoms with lead dioxide and recovering from the resultant oxidation product a tetra-substituted stilbene quinone.

35 13. A process for producing a tetra-substituted stilbene quinone in which the substituents are selected from the members of the group consisting of an alkyl group and an alkoxy group each containing from one to six carbon atoms which comprises treating a member of the group consisting of a di-alkyl-p-cresol and a di-alkoxy-p-cresol in which the alkyl and alkoxy groups contain from one to six carbon atoms with silver oxide and recovering from the resultant oxidation product a tetra-substituted stilbene quinone.
